FIG. 1

FIG. 2

FIG. 3

FIG. 1 is a front, top and right side perspective view of a combined phonograph and tuner showing our new design;

FIG. 2 is a front elevational view; and

FIG. 3 is a right side elevational view.

The appearance of the pedestal portion of the base is the same on all sides. The rear is flat and is comprised of transparent and opaque surfaces of the same relative height and location as those on the side shown in FIG. 3.

We claim:

The ornamental design for a combined phonograph and tuner, substantially as shown and described.
